(57) **CLAIM**

The ornamental design for a LED panel light, as shown and described.

DESCRIPTION

FIG. 1 is a top plan view of a LED panel light showing our new design;

FIG. 2 is a bottom plan view thereof;

FIG. 3 is a left side view thereof;

FIG. 4 is a front elevational view thereof;

FIG. 5 is a perspective view thereof; and,

FIG. 6 is another perspective view thereof.

The right side view is symmetrical to the left side view, and the rear elevational view is symmetrical to the front elevational view.

The broken lines shown in LED panel light form no part of the claimed design.
